UNITED STATES PATENT OFFICE.

EDWARD J. VON PEIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,190,489.

Specification of Letters Patent. Patented July 11, 1916.

Application filed October 1, 1913. Serial No. 792,909.

To all whom it may concern:

Be it known that I, EDWARD J. VON PEIN, a citizen of the United States, residing at Dayton, in the county of Montgomery and 5 State of Ohio, have invented certain new and useful Improvements in Cash-Registers, of which I declare the following to be a full, clear, and exact description.

This invention relates to cash registers or 10 accounting machines and has particular reference to the printing mechanism of such machines.

While one object of the invention is to provide a ticket issuing machine that is 15 simple in construction and can be manufactured at a low cost, and in the following description and the accompanying drawings the invention is treated as applied to a cash register designed for use in a theater ticket 20 office, it is not the intention to limit the use of the idea to such machines.

The invention is a broad one and is applicable in various forms to cash register and accounting machine printing mechanisms in 25 general, and not simply to the printing mechanisms of machines designed for one particular line of business.

In previous constructions the value printing type carriers and the paper feeding devices have been entirely separate and distinct, but operated in certain relations one to the other by a main operating mechanism. In the present construction, and this is a broad object of the invention, the type carrying and paper feeding functions are combined in one element, thereby greatly simplifying the construction of the printing mechanism and lessening the chances of its getting out of adjustment. It should be understood, however, that it is not the desire to be limited to a feeding element such as is shown in this embodiment of the improvement, as the idea can be applied to many other forms of feeding or impression devices with just 45 as satisfactory results.

In the construction disclosed by this application a paper feeding element carries a plurality of independent type carriers each bearing the characters to represent one of the 50 keys on the keyboard.

Another object of the invention is to pro-

vide devices which are positively and differentially positioned when a key is pressed so that the type carrier corresponding to the key used will be inked and caused to make an 55 impression when the paper is fed by the feeding device.

As applied to show ticket issuing machines one object of the invention is to provide a machine that will print and issue tickets of 60 admission as they are called for by patrons. In this way the expense of providing and carrying on hand more tickets than may be needed is done away with and there is no 65 possibility of losses on account of valid tickets being stolen from the ticket office.

Another object is to provide a simply constructed ticket issuing machine in which the amounts received for tickets are automatically added on a totalizer as the tickets are 70 issued.

With these and incidental objects in view, the invention consists in certain novel features of construction and combinations of parts, the essential elements of which are set 75 forth in appended claims, and a preferred form of embodiment of which is hereinafter described with reference to the drawings which accompany and form part of the specification.

Of said drawings: Figure 1 represents a vertical section of a cash register and shows a part of the improvement assembled in position. Fig. 2 is a left side elevation of a cash register with the outside frame of the printing mechanism removed. Fig. 3 is a bottom plan view of the paper feeding and printing cylinder. Fig. 4 is a rear view partly in section of the paper feeding and printing cylinder and shows the amount printing 90 plungers and their operating mechanism. Fig. 5 is a group of details showing in section the paper feeding and printing cylinder, the inking roll and the impression roll. These details not only show features of the 95 construction, but, taken as a whole, show the normal operative relation of the parts when in position in the machine. Fig. 6 represents a ticket issued by the illustrative machine.

The cash register in which this embodiment of the invention is shown is the one

fully described in United States Letters Patent 580,378 granted April 13th, 1897, to J. P. Cleal and F. A. Reinhard, while the printing cylinder used is shown and described in United States Letters Patent 541,247 issued June 18th, 1895, to William Murphy. Reference may be had to those patents for a complete description of such parts of the register and cylinder as are not described in the present application. However, this embodiment is illustrative only as there are a number of other similar devices on the market to which the invention could be applied to almost equal advantage.

As shown, the illustrative machine has three keys, each for registering the sales of tickets sold at a certain price; in this instance 5¢, 10¢ and 15¢ respectively. The Murphy cylinder for printing the date and consecutive number of the sale and which also feeds the paper is by the invention provided with an extension in the form of a drum carrying printing plungers, one for each of the keys of the machine, bearing characters corresponding to the captions on their respective keys. Depressing a key to record the sale of a ticket positively positions a cam bearing device inside of the drum so that when the cylinder is rotated in the operation of the machine the plunger corresponding to the key depressed will be carried across the projections of the corresponding cam and forced out twice; the first time to receive ink from an ink roll and the next time to print on the ticket that is being fed through. During the operation the amount received for the ticket is automatically added on a totalizer. The printer is so arranged that the ticket is issued at the rear of the machine. The purpose of this is to make it possible to place the register with the front or key side toward the operator and with the receiver into which the ticket is issued extending through the ticket window. This makes the ticket accessible to the patron but not to the operator, and would make noticeable any attempt to resell used tickets.

Explaining the machine in detail and with reference to the drawings, the 5¢, 10¢ and 15¢ keys are represented by the numerals 1, 2 and 3 respectively (see Fig. 1). When one of these keys is pressed in it is held in the depressed position by a detent 4 and a retaining bar 5 with the inner end of the key extending into the path of the trip 71 for the latch 72 carried by a segment 73 which is loosely journaled on a shaft 74. Attached to the shaft 74 is a plate 75 and a crank 76, and attached to the shaft 77, which is one of the main driving shafts of the machine and is given a complete rotation on every operation of the machine, is a crank 78. A link 79 connects the cranks 76 and 78. As the crank 78 is shorter than the crank 76, every

time the shaft 77 rotates the shaft 74 and the plate 75 attached to it are rocked through an arc of about 90°. At the beginning of the operation the latch 72 engages the plate 75 and the segment 73 is carried up until the latch trip 71 strikes the end of the key depressed, tripping the latch and disconnecting the segment 73 from the plate 75 and projecting the end of the latch 72 into engagement with a notch such as shown at 81 in a plate attached to the key frame and holding it in engagement until the operation of the machine is completed. The teeth of the segment 73 are always in engagement with the teeth of a gear 811 and during the time the segment is moving the gear 811 is rotated, and, of course, it stops when the segment 73 is stopped by the tripping of the latch 72. This differential movement of the segment 73 and the gear 811 is transmitted through a gear 82 and an intermediate pinion 83 to a totalizer wheel 6, causing the totalizer wheel to be rotated the proper number of divisions to represent the value of the key depressed. The gear 811 also transmits the differential motion to an indicator 84 through a pinion (not shown) rigid with the gear 811 and meshing with a gear 85 attached to the side of an indicator 84. This mechanism is shown and described in greater detail in the Cleal and Reinhard patent cited above and reference may be had to that patent for any further information desired regarding the construction or operation of the devices mentioned.

The printer comprises a cylinder 8 attached to the end of a shaft 7, which makes a complete rotation on every operation of the register, an impression roll 9 attached to a shaft 10 journaled in printer side frames 11 and 12 (Figs. 2, 3 and 4), the inking roll 13 turning on a rod 14 supported by the printer side frames 11 and 12, and the knives 15 and 16 for severing tickets from a ticket strip 17. Attached to the shaft 10 and between the inner printer frame 11 and the machine frame 18 is a gear 19 always in mesh with a gear 21 attached to the driving shaft 7. Each time the shaft 7 is rotated both the impression roll 9 and the cylinder 8 are given complete rotations. A supply roll 22 of ticket strip 17 is carried on a stub shaft 23 in the casing of the machine and the paper passes from this supply roll up over a guide 24 between the cylinder 8 and the impression roll 9 and through the slot of a paper guide 25 to the knives 15 and 16.

After the ticket has been printed and fed the proper distance it is severed from the ticket strip by the knives 15 and 16 and drops in a receiver 26. The ticket strip is fed from the supply roll 22 by the feeding flange 27 attached to the cylinder 8 and a plate 28 attached to a part of the cylinder which contains the amount printing devices.

Ordinarily the paper rests loosely between the cylinder 8 and the impression roll 9, but when the cylinder and roll are rotated as above described the feeding flange 27 and the plate 28 press the ticket paper against the impression roll thereby gripping the paper and drawing it from the supply roll as long as the flange 27 and the plate 28 are in contact with the paper. The width of the ticket from top to bottom depends upon the length of the flange 27 and plate 28, as the longer they are the longer they grip the paper and the more paper is pulled from the supply roll on each operation of the machine. Attached to the end nearest the machine of the impression roll 9 is a cam with a groove 31. In this groove there operates an anti-friction roll 32 carried by an arm 33 pivoted at 34 to the inside printer frame 11 and at 35 to a laterally extending plate 36 which is slidably mounted at one side in a guide way 37 which is a part of the inside printer frame 11. Attached to the plate 36 is the upper knife 16. It will be seen that each time the impression roll is rotated the knife 16 will be carried down so that it will act in connection with the lower knife 15, which is rigidly attached to the printer frame 11, in such a way as to sever the ticket strip 17, after which the knife 16 is returned to its original position.

As shown in Fig. 3 the cylinder 8 carries wheels 38 for printing the consecutive numbers of the tickets issued and wheels 41 for printing the date on which the ticket was sold. Above and below the space through which these wheels extend there may be attached type carriers in the form of electros to print advertising matter or announcements such as are shown on the sample ticket in Fig. 6. This construction is fully explained in the Murphy patent above cited and needs no detailed description here. The usual shell of the cylinder is extended so as to provide a drum or compartment in which the amount printing mechanism of this invention is placed (see Fig. 4). Mounted in the shell of the drum and extending through suitable holes in the plate 28 are plungers 42. The heads of these plungers are normally held against the disks 43 by springs 40 pressed between the heads of the plungers and the inside of the plate 28. The disks 43 and a series of cams 44, 45 and 46 for operating the 5¢, 10¢ and 15¢ plungers respectively are all rigidly fastened to a shaft 7^a which is in axial alignment with the drive shaft 7 and is journaled at one end in the outside printer frame 12, thereby forming one of the supports on which the cylinder turns, and has the other end rotating freely in a bearing provided in the transverse wall 47 separating the two compartments of the cylinder. The outer end 65 of the compartment in which the amount

printing devices are located is closed after the parts are assembled in position by a cap plate 48. This cap plate is fastened to the cylinder shell and turns with the cylinder independent of the shaft 7^a. Secured to the shaft 7^a and adjoining the cap plate 48 is a gear 49 the purpose of which will appear later in this description.

Each of the registering keys (Fig. 1) has a pin 51 extending at right angles to the shaft of the key. When the keys are pressed in these pins strike a lever 52 rigidly attached to a rock shaft 53 journaled in the key bank frame 50, the casing 24 and the printer frames 11 and 12. A stop stud 62 holds the lever 52 in the position shown, while a stud 63 serves as a stop to fix the greatest extent of movement possible for the lever. The lever 52 is so graduated that the pin of each key will impart a different extent of movement to the lever and consequently turn the rock shaft different degrees. Attached to the end of the rock shaft 53 just inside of the outside printer frame 12 is a long gear segment 54 (Fig. 2) the teeth of which are always in mesh with the gear 49 attached to the shaft 7^a. When one of the registering keys is pressed in and the shaft 53 rocked the segment 54 is swung up a distance depending upon which key is pressed, rotating the gear 49, the shaft 7^a and the cams attached to the shaft to bring the proper one of the cams into effective position. When the depressed key is released near the end of the operation of the machine the force of gravity is depended upon to pull the segment 54 downwardly, thereby restoring it and its associated parts to normal position. It is obvious, of course, that a spring may also be employed to assist the force of gravity in restoring these parts to normal. The shape and axillary displacement of the cams 44, 45 and 46 on the shaft 7^a are best shown in Fig. 5. Each cam has two operating projections, one to operate its plunger 42 to take ink from the ink roll 13 and the other to operate the plunger to make an impression on the ticket. The projections to operate the plungers to take ink are designated by the numeral 55 and the projections to operate them to make the impression are designated by the numeral 56 (Fig. 5). When a key is depressed the inking projection 55 of the corresponding cam will be opposite the point 57 of the ink roll 13 and the impression operating projection 56 will be opposite the printing line 58 of the impression roll 9. The cams remain in this position while the machine is operated. During the operation the cylinder is rotated, carrying the plungers along and causing them to pass over the projections 55 and 56 of their cams. However, the cams are spirally mounted around the shaft 7^a in such a way that only one of the cams has 130

its projections at the effective positions 57 and 58 and only the plunger working with that cam will be inked or make an impression on the ticket paper. The other plungers will be operated but as they are operated out of effective position they neither ink nor print.

As so far described it will be seen that the friction between the plungers 42 and their operating cams would have a tendency to cause the cam to be carried along with the plungers when they come in contact. This might rotate the shaft 7^a and the gear 49, raising the segment gear 54 and rocking the shaft 53 until the lever 52 was stopped by the stop stud 63, which would result in printing 15¢ on every operation regardless of the key pressed. To prevent this there is provided a pawl 64 (Fig. 2) loosely pivoted at 65 to the outside printer frame 12 with a nose 66 resting in the notches of a plate 67 attached to the side of the segment gear 54. As the segment 54 is raised and lowered during operation the nose of the pawl passes idly over the teeth of the plate. However, as soon as the segment gear 54 has been placed by the key and the machine operated far enough to bring the feeding plate 28 (Fig. 5) into contact with the extension 68 of the pawl 64, the nose 66 of the pawl is firmly held in engagement with the teeth of the plate 67 until both the inking and printing movements of the plungers are completed. In this way the drag of the plungers 42 across the projections of their cams is prevented from displacing the cams and causing the wrong amounts to be printed.

To summarize the operation of the device, a brief description of what occurs when a 15¢ ticket is sold will next be given. The 15¢ key 3 (Fig. 1) is pressed in and retained in its depressed position by the mechanism provided for that purpose. As the key is forced in it contacts the graduated lever 52 and rocks the shaft 53 to which the lever is attached and carries the gear segment 54 attached to the same shaft a corresponding distance. The gear segment rotates shaft 7^a carrying the series of cams each having two projections 55 and 56, the first to ink the type and the latter to print on the ticket paper. These cams are so arranged on their shaft 7^a that the projections of only one of the cams will be at the inking and printing positions during an operation so that while all of the plungers are operated during a rotation of the cylinder which carries them, only one of the plungers will ink and print. After the cams have been positioned so that the one corresponding to the 15¢ key has its projections in the effective positions and the mechanism is started the segment gear is locked in position by the pawl 64 so that it cannot be displaced until near the end of the operation of the machine. Then as the

cylinder 8 is rotated by the turning of the main drive shaft 7 to which the cylinder is attached, the 15¢ plunger passes over the two extensions above mentioned of the cam. As it passes the extension 55 the plunger is cammed out against the tension of the spring 40 so that the type come in contact with the ink roller 15 and are given a supply of ink. The plunger is then carried back by its spring to normal position and remains there until it reaches the extension 56 on the cam 46, when it is again cammed out so the type make an impression on the ticket paper 17. Further operation serves the ticket from the ticket strip and allows it to drop into the receiver provided for that purpose and the weight of the segment 54 causes it to drop back to normal, thereby returning all of the parts of the device to the positions shown in the drawings.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

What is claimed is:—

1. In a machine of the class described, the combination of a movable type carrier, its type being capable of movement independent of movement of the carrier, means for moving the carrier, means for imparting independent movement to all of the type in an invariable sequence during the movement of the carrier, a platen, and means for determining which type is to be moved while in co-operative relation with said platen to take an impression.

2. In a machine of the class described, the combination with a driving means, of a type carrier driven by said driving means, the type being capable of movement independent of the movement of their carrier, means for giving the independent movement to all of the type in an invariable sequence, a platen, and means for determining which type is to be moved while in co-operative relation with said platen.

3. In a machine of the class described, the combination of a movable type carrier, its type being capable of movement independent of the movement of the carrier, means for moving the carrier, means for imparting independent movement to all of the type during the movement of their carrier, a platen, an ink supplying device, and manipulative means for determining which type will be moved while in co-operative relation with the inking device and the platen.

4. In a machine of the class described, the combination with an operating mechanism, of a platen, a movable type carrier, its type

- being arranged to come simultaneously in coöperative relation to the platen, means for projecting all of the type from the carrier during an operation of the operating mechanism, and means for determining the type to be projected while in coöperative relation with the platen.
5. In a machine of the class described, the combination with driving mechanism, of a 10 rotary type carrier, the type being arranged longitudinally of the type carrier, cams for projecting all of the type from the carrier during an operation of the driving mechanism, a platen, and a plurality of keys whereby said cams may be differentially positioned to project any desired type while in coöperative relation with the platen.
6. In a machine of the class described, the combination with operating devices, of a 20 platen, a rotary type carrier, its type being arranged longitudinally of the type carrier, means for projecting all of the type from the carrier during an operation of the operating devices, and manipulative means for determining the type to be projected while in coöperative relation with the platen.
7. In a machine of the class described, the combination of a ticket issuing mechanism comprising an element having an invariable 30 movement on every operation of said mechanism, a plurality of type carriers carried bodily by said invariably moved element and manipulative means for predetermining which of said type carriers is to print on an operation of the ticket issuing mechanism.
8. In a machine of the class described, the combination of a ticket issuing mechanism comprising an element having an invariable movement on every operation of the 40 mechanism, a plurality of type bearing plungers carried bodily by said invariably moved element, and manipulative means for predetermining which of said plungers is to print on said operation.
9. In a machine of the class described, the combination of a ticket issuing mechanism comprising an element having an invariable movement on every operation of the mechanism, a plurality of type carriers carried 50 by said invariably moved element, manipulative devices, and means differentially positioned by said manipulative devices to predetermine which of said type carriers is to print on the ticket issued.
10. In a machine of the class described, the combination of a ticket issuing mechanism comprising an element having an invariable movement on every operation of the mechanism, a plurality of type carriers carried 60 by said invariably moved element, an inking roll, manipulative devices, and means differentially positioned by said manipulative devices to predetermine which of said type carriers is to be inked on an operation of said mechanism.
11. In a machine of the class described, the combination with printing devices comprising an element having an invariable movement on every operation of the mechanism, of a plurality of type carriers carried bodily by said invariably moved element, devices for giving said type carriers invariable excursions in addition to the movement of the invariably moved element, a platen, and means for positioning 70 said devices to predetermine which of the type carriers is to be given an excursion while in coöperative relation with said platen.
12. In a machine of the class described, the combination with an operating mechanism, of a type carrier carrying a plurality of aligned type, means for moving all type from the carrier at an operation of the machine, a platen, and means for determining 75 which type will coöperate with the platen to print on an operation of the operating mechanism.
13. In a machine of the class described, the combination with an operating mechanism, of a type carrier carrying a plurality of aligned type, means for moving all type from the carrier at an operation of the machine, a platen, and manipulative devices for predetermining which type will coöperate 80 with the platen to print on an operation of the operating mechanism.
14. In a machine of the class described, the combination with an operating mechanism, of a plurality of type, means for operating all of the type during an operation of the operating mechanism but not simultaneously, a platen, and means for predetermining which of the operated type is to coöperate with said platen.
15. In a machine of the class described, the combination with a ticket feeding element, of a plurality of type carriers carried by said feeding element, and manipulative means for determining which of said type carriers is 90 to print on an operation of the ticket feeding element.
16. In a machine of the class described, the combination with an operating mechanism, of a ticket issuing mechanism comprising a feeding device having an invariable extent of movement, a plurality of printing elements carried by said feeding device, and manipulative means for predetermining which of said printing elements is to print 100 on an operation of the operating mechanism.
17. In a machine of the class described, the combination with a register operating mechanism, of a printing mechanism comprising an element to feed a record material on each 110 operation of said register operating mechanism, a plurality of printing elements carried bodily by said feeding element, and manipulative means for predetermining which of said printing elements is to print 120 on an operation of the operating mechanism.

8
on an operation of the aforesaid feeding element.

18. In a machine of the class described, the combination with an operating mechanism, of a ticket issuing mechanism comprising a feeding device having an invariable extent of movement, a plurality of printing elements carried by said feeding device, means for inking said printing elements, and manipulative means for predetermining which of said printing elements is to be inked on an operation of the operating mechanism.

19. In a machine of the class described, the combination with ticket issuing devices comprising a rotatable paper feeding cylinder, of a plurality of type bearing plungers carried bodily by said feeding cylinder when it rotates, and a plurality of keys for determining which of said plungers is to print on a rotation of the paper feeding cylinder.

20. In a machine of the class described, the combination with a main operating mechanism, of a ticket printing mechanism comprising a rotatable paper feeding element, a plurality of type carriers carried bodily by said feeding element when it rotates, and means for predetermining which of said type carriers is to operate on an operation of the main operating mechanism.

21. In a machine of the class described, the combination with an operating mechanism, of a ticket printing mechanism comprising a rotatable paper feeding element, a plurality of normally ineffective printing elements carried bodily by said feeding element when it rotates, and manipulative means for selectively rendering said printing elements effective to print on an operation of the operating mechanism.

22. In a machine of the class described, the combination with an operating mechanism, of an accounting device, manipulative devices for determining amounts to be entered in the accounting device by operations of the operating mechanism, ticket issuing devices comprising a feeding element, a plurality of independent printing elements carried by said feeding element; and means controlled by the aforesaid manipulative devices for determining which of said printing elements is to print on an operation of the operating mechanism.

23. In a machine of the class described, the combination with a registering device, of a ticket issuing mechanism comprising a paper feeding element, a common operating mechanism for said registering device and ticket feeding element, a plurality of type carriers carried by said feeding element, and manipulative means for determining which of said type carriers is to print on an operation of said common operating mechanism.

24. In a machine of the class described, the combination with a registering device, of operating mechanism therefor, manipulative

devices for determining amounts to be entered in the registering device by operations of an operating mechanism, ticket issuing devices comprising a feeding element, a plurality of printing elements carried by said feeding element, and means controlled by the aforesaid manipulative devices for predetermining which of said printing elements is to print on an operation of the operating mechanism. 70

25. In a machine of the class described, the combination with ticket issuing devices comprising a rotatable paper feeding cylinder, of a plurality of type bearing plungers carried bodily by said feeding cylinder when it rotates, a plurality of keys, and a plurality of cams differentially positioned by said keys to predetermine which of said type bearing plungers is to print on a rotation of the aforesaid paper feeding cylinder. 75

26. In a machine of the class described, the combination with a main operating mechanism, of an accounting device, value determining keys under the control of which amounts are entered in said accounting device by operations of the main operating mechanism, a printing mechanism comprising a rotatable cylinder which carries devices to feed a ticket and print thereon the consecutive number, date and amount of each transaction entered in the accounting device, and devices positively positioned by operation of the value determining keys whereby the value represented by the key used will be printed on the ticket when the 100 aforesaid cylinder is rotated.

27. In a machine of the class described, the combination with an accounting device and operating mechanism therefor, of a ticket issuing device comprising an element to feed 105 a ticket on each operation of the accounting device operating mechanism, a plurality of amount printing devices carried by said ticket feeding element, and means for predetermining which of said amount printing devices is to print on an operation of the aforesaid operating mechanism. 110

28. In a machine of the class described, the combination with a totalizer, of an operating mechanism therefor, means for predetermining the amounts to be entered in the totalizer by operations of the operating mechanism, a ticket issuing mechanism comprising a rotatable feeding element, a plurality of normally ineffective printing elements carried bodily by said feeding element, and devices positively operated by the aforesaid predetermined means for selectively rendering said printing elements effective. 115

29. In a machine of the class described, the combination with an accounting machine, of a plurality of manipulative devices for entering amounts in said accounting machine, a ticket printing mechanism 120

comprising a rotatable paper feeding device, a plurality of normally ineffective printing elements carried bodily by said rotatable paper feeding device, and means whereby 5 operation of one of aforesaid manipulative devices to enter an amount in the accounting machine will render a certain one of the printing elements effective.

30. In a machine of the class described, 10 the combination with an accounting machine, of a plurality of manipulative devices for entering amounts in said accounting machine, a ticket printing mechanism comprising a rotatable feeding device having 15 an invariable extent of movement, a plurality of printing elements carried bodily by said rotatable paper feeding device, and means differentially positioned when any of the aforesaid manipulative devices is operated whereby the printing element corresponding to the manipulative device used will be rendered effective to print on an 20 operation of the accounting machine.

31. In a machine of the class described, 25 the combination with a movable type carrier, its type being capable of movement independent of movement of the carrier, of means for moving the carrier, means for imparting independent movement to all of the 30 type in an invariable sequence during the movement of the carrier, a platen, an ink supplying device, and means for determining which type is to be moved while in co-operative relation with said platen and ink 35 supplying device.

32. In a machine of the class described, the combination with an operating mechanism, of a platen, an inking device, a movable type carrier, its type being arranged to 40 come simultaneously in co-operative relation to the platen, means for projecting all of the type from the carrier during an operation of the operating mechanism, and means for determining the type to be projected while in co-operative relation with the 45 platen and the inking device.

33. In a machine of the class described, the combination with driving mechanism, of a rotary type carrier, the type being arranged 50 longitudinally of the type carrier, cams for projecting all of the type from the carrier during an operation of the driving mechanism, a platen, and means whereby said cams may be positioned differentially 55 to project any desired type while in co-operative relation with the platen.

34. In a machine of the class described, the combination with a ticket issuing mechanism, comprising an element having an in- 60 variable movement on every operation of the mechanism, of a plurality of type bearing plungers carried bodily by said invariably moved element, and selectively operated to print and manipulative means for selecting 65 the plungers to print.

35. In a machine of the class described, the combination with a ticket feeding element, of a plurality of type carriers carried by said feeding element, printing means co-operating with the type carriers, and means 70 for determining which of said type carriers is to print on an operation of the ticket feeding element.

36. In a machine of the class described, the combination with a ticket feeding element, of a plurality of type carriers carried by said feeding element, printing means co-operating with the type carriers, an inking device, and manipulative means for determining which of said type carriers is to be 75 inked and to print on an operation of the ticket feeding element.

37. In a machine of the class described, the combination with an operating mechanism, of a ticket issuing mechanism, comprising a feeding device having an invariable extent of movement, a plurality of printing elements carried by said feeding device and selectively operated to print on tickets, means for inking the printing elements selected to print, and means for selecting the printing elements to be inked and to print. 85

38. In a machine of the class described, the combination with a ticket issuing device, 90 comprising a rotatable paper feeding cylinder, of a plurality of type bearing plungers carried bodily by said feeding cylinder and selectively operated to print, and means for selecting which of the plungers is to 100 print during a rotation of the paper feeding cylinder.

39. In a machine of the class described, the combination with an operating mechanism, of a ticket printing mechanism comprising a rotatable paper feeding element, a plurality of normally ineffective printing elements carried bodily by said feeding element when it rotates, and means for selectively rendering said printing elements effective to print on an operation of the operating mechanism. 105

40. In a machine of the class described, the combination with a movable type carrier, its type being selectively actuated to 110 print during movement of the carrier, of means for selectively actuating the type to print.

41. In a machine of the class described, the combination with a rotatable type carrier, its type being selectively actuated to print during rotation of the carrier, of means for selectively actuating the type to print. 120

42. In a machine of the class described, the combination with an inking device, of a movable type carrier, its type being selectively actuated to be inked during movement of the carrier, and means for selecting the type to be inked. 125

43. In a machine of the class described, the combination with an inking device, of a movable type carrier, its type being selectively actuated to be inked and to print during movement of the carrier, a printing platen coöperating with the type carriers, and means for selectively actuating the type.

In testimony whereof I affix my signature in the presence of two witnesses.

EDWARD J. VON PEIN.

Witnesses:

R. C. GLASS,
CARL W. BEUST.
